UNITED STATES PATENT OFFICE.

JOHN S. CURTISS, OF EL PASO, TEXAS.

DESIGN FOR A SLOT-MACHINE SAVINGS-BANK.

51,366.

Specification for Design.

Patented Oct. 16, 1917.

Application filed February 7, 1917. Serial No. 147,266. Term of patent 14 years.

To all whom it may concern:

Be it known that I, JOHN S. CURTISS, a citizen of the United States, resident of El Paso, in the county of El Paso and State of Texas, have invented a new, original, and ornamental Design for a Slot-Machine Savings-Bank, of which the following is a specification, reference being had to the accompanying drawing, forming a part thereof.

The drawing represents a front elevation of the device.

I claim:

The ornamental design for a "slot machine savings bank", as shown.

JOHN S. CURTISS.
